UNITED STATES PATENT OFFICE

JAMES S. OGSBURY, OF DAYTON, OHIO, ASSIGNOR TO INTERNATIONAL TIME RECORDING COMPANY, OF NEW YORK, OF ENDICOTT, NEW YORK, A CORPORATION OF NEW YORK

PRINTING ATTACHMENT FOR PAY ROLL RECORDER

Application filed September 24, 1928. Serial No. 307,951.

This invention relates to time recording apparatus and provides special advantages in combination with time recorders of the so called dial type.

As it is well known this type of time recorder is provided with a drum carrying a time sheet. The drum is located opposite the time controlled printing device and each line of the drum may be adjusted into printing position by means of a manually operable lever connected with the drum. The lever in turn may be adjusted on a dial provided with distinguishing numbers so that each number on the dial corresponds to a predetermined identical printing space of the time sheet. When at the end of a working period the sheet is removed from the recorder, it will show the time at which each workman being indicated by its number entered and left and the elapsed time and the due wages may be calculated accordingly and recorded upon the same sheet thus obtaining the payroll.

Up to the present this payroll had to be completed by entering the workmen's names, either by hand or typewriting. The present application provides a time recorder including a printing mechanism for printing upon the time sheets the workmen's names in the proper places on the sheet.

A further object of the invention is to provide a printing drum within a time recorder with interchangeable type slugs to print upon the time sheet identifying characters corresponding to the different positions of the type drum.

A further object of the invention is to provide means to selectively effect printing of the identifying characters upon the time sheet.

A further object of the invention consists in the provision of adjusting means to secure proper relative adjustment between the time sheet drum and the printing device for identifying characters.

Other objects and advantages will be hereinafter set forth in the accompanying specification and claims and shown in the drawings which show by way of illustration what is now considered to be the preferred embodiment of the invention.

Fig. 1 of the drawings shows a general view of a dial time recorder, the rear plate of the housing being omitted;

Fig. 2 represents the printing device according to the present invention in its operative position;

Fig. 3 is a sectional view through the printing device according to Fig. 2;

Fig. 4 is a sectional view according to line 4-4 of Fig. 3;

Fig. 5 shows a detail of Fig. 1;

Fig. 6 shows a detail of the printing device;

Fig. 7 illustrates a time sheet;

Fig. 8 shows a modification of the printing mechanism.

In Fig. 1 the numeral 4 designates the housing enclosing the time recording and printing mechanism generally designated at 1 and a drum 2 carrying a time sheet 3 (Fig. 3). Drum 2 is fixed upon shaft 5 carrying a lever

6. By means of a handle 7 and adjusting holes in the dial 8, lever 6 and consequently drum 2 may be adjusted to different printing positions. It is obvious that to each adjusting position of the dial only one predetermined printing position and printing space of the time sheet is coordinated.

According to this invention there is provided a second printing device consisting of a drum 10 provided with interchangeable type slugs 11 (see Figs. 1-3). Drum 10 is mounted upon shaft 12, the latter being loosely located in bearings 13 and 14. Bearings 13 and 14 are resiliently and slidably arranged on plates 15 one on each side of the drum, said plates being connected with a frame 16 rockable upon shaft 17.

On frame 16 is provided a grooved pin 18 and on drum 10 a spring pressed ball 19 to secure adjustment of the drum in a proper normal or starting position. Frame 16 carries a roll 20 provided with a printing ribbon

21. Shaft 17 upon which the printing frame is rockable is fixed on the housing and forms a part of frame 23. A lower projection 24

of frame 16 is pivotally connected with rod member 25 which in turn is pivotally connected at its lower end with plate 26 pivotally mounted at 27 and provided with a handle 28. If handle 28 is in the position

shown in Fig. 1 printing drum 10 will not touch time sheet drum 2 but when handle 28 is moved downwardly frame 16 will be rocked counterclockwise and drum 10 will be pressed towards drum 2 so that printing may take place when drum 2 (Fig. 1) is turned counterclockwise by means of lever 6.

To secure proper relative adjustment between time sheet drum and type drum besides grooved pin 18 and ball 19 there is provided an adjusting member 22 fixed upon the dial (see Fig. 5). Member 22 is provided with a pin 30 passing into the last hole of the dial and with two lugs 31, 32, forming stops for stem 29 of the time drum handle.

When stem 29 is in contact with stop 32 and type drum 10 is in its normal position handle 28 may be pressed down thus pressing the type drum against the time sheet drum. Lever 6 then may be turned one full revolution to stop 31 and back and it will be understood that all names on the type lugs will be printed upon the time sheet (see Fig. 7).

A modification of the adjusting mechanism and the printing device are shown in Fig. 8. The type drum 10 is provided with a member 33 passing in the usual slot 34 of the time drum serving to fasten the ends of the time sheet. Instead of the ribbon printing rolls 35 are used pivotally mounted upon frame 16 and pressed against type drum 10 by means of spring 36.

It is one of the essential advantages of the present invention that the printing device may be accommodated immediately to the latest requirements. For this purpose the type lugs 11 are interchangeable. Upon shaft 12 (see Figs. 3 and 6) is loosely mounted disk 37 provided with a spring plate 38 having a pin 39 which passes into a hole of type drum 10 to secure disk 37 in a certain position. Disk 37 has a slot 40 opposite which there are no slugs. If any slug has to be changed spring plate 38 and pin 39 are pulled outwardly and slot 40 of disk 37 is turned to the respective slot 41. Then the type slug may be removed and a new one inserted. Disk 37 is then turned back again to its normal position where it is secured by pin 39.

While there has been shown and described the fundamental novel features of the invention as applied to two modifications it will be understood that various omissions and substitutions and changes in the form and details of the device illustrated and in its operation may be made by those skilled in the art without departing from the spirit of the invention. It is the intention therefore to be limited only as indicated by the scope of the following claims.

For instance, while the illustrations of the invention show type slugs adapted to be inserted in the printing drum, it is obvious that individual type elements instead of com-

plete type slugs may be employed. In this connection the slots for holding the type elements may be made across the drum and the type elements inserted from the side.

I claim:

1. In combination, a carrier having a sheet fixed thereto, said sheet having a plurality of divisions and a printing roll having a plurality of removable, interchangeable devices, each intended for printing in one of said divisions, and means for preventing free removal until desired of said devices from the roll.

2. In combination, a carrier for a sheet provided with a plurality of divisions, printing means having separate devices, each intended for printing only in a predetermined corresponding division, an indicator having designations corresponding to said divisions, manual means for moving said printing means and carrier relatively to effect printing by said devices in the corresponding divisions, and positioning means carried by said indicator for abutting the manual means at the beginning and end of the movement of the latter.

3. In combination, a rotary member for carrying a sheet bearing a plurality of parallel divisions, a rotary printing member normally spaced from the other member and provided with a plurality of devices, each intended for printing only in a corresponding one of said divisions, means for moving said rotary members into engagement, and means for rotating the members in opposite directions through frictional engagement therebetween to effect printing by each device in the corresponding division.

4. In combination, a rotary cylinder for carrying a sheet bearing a plurality of parallel divisions, a rotary printing cylinder for carrying a plurality of parallel printing devices, each intended for printing only in a corresponding one of said divisions, means for initially retaining said printing cylinder in its starting position, means for rotating the sheet-carrying cylinder to frictionally rotate the printing cylinder and cause printing on the sheet, and means for locating the position at which the sheet carrying cylinder starts to frictionally rotate the other cylinder.

5. In combination, a rotary cylinder for carrying a sheet bearing a plurality of circumferentially arranged divisions, a rotary printing cylinder carrying a plurality of circumferentially arranged devices, each intended for printing only in a corresponding one of said divisions, said cylinders being normally spaced apart, manual means for moving said cylinders into engagement, means for retaining said printing cylinder in a predetermined position, manual means for rotating the sheet-carrying cylinder after engagement thereof with the printing cylinder to effect printing by the latter, an indicator cooperat-

ing with the latter manual means to determine the starting and stopping positions of the said latter means, and means carried by the indicator for stopping the said latter manual means at the end of its movement.

5. 6. In combination, a pair of spaced apart rotary members of a printing couple, one carrying a record sheet having parallel fields, the other carrying printing elements each for 10 printing in a corresponding field, means for moving the members towards each other into engagement, means for thereafter rotating the members to effect printing, and means for assuring that each element will print in the 15 proper field, comprising means for initially retaining one of said members in a predetermined position, and means for rotating the other member to a predetermined position preliminarily to the engagement of the members.

20. In testimony whereof I hereto affix my signature.

JAMES S. OGSBURY.
